CLAIM

The ornamental design for a canister cap as shown and described.

DESCRIPTION

1. Canister cap
3. Canister cap
4. Canister cap
- 1.1 : Perspective
- 1.2 : Perspective
- 1.3 : Front
- 1.4 : Back
- 1.5 : Left
- 1.6 : Right
- 1.7 : Top
- 1.8 : Bottom
- 3.1 : Perspective
- 3.2 : Perspective
- 3.3 : Front
- 3.4 : Back
- 3.5 : Left
- 3.6 : Right
- 3.7 : Top
- 3.8 : Bottom
- 4.1 : Perspective
- 4.2 : Perspective
- 4.3 : Front
- 4.4 : Back
- 4.5 : Left
- 4.6 : Right
- 4.7 : Top
- 4.8 : Bottom

(Continued)

In the drawings, the broken lines depict portions of the canister cap that form no part of the claimed design.
